UNITED STATES PATENT OFFICE.

PETER M. KLING, OF ST. LOUIS, MISSOURI.

BUFFER FOR STREET-CARS.

SPECIFICATION forming part of Letters Patent No. 660,903, dated October 30, 1900.

Application filed June 11, 1900. Serial No. 19,851. (No model.)

To all whom it may concern:

Be it known that I, PETER M. KLING, a citizen of the United States, residing at the city of St. Louis, in the State of Missouri, have

5 invented certain new and useful Improvements in Buffers for Street-Cars, of which the following is a full, clear, and exact description, reference being had to the accompanying drawings, forming part of this specification.

10 My invention relates to an improved buffer for street-cars; and it consists in features of novelty hereinafter fully described, and pointed out in the claim.

15 Figure I is a side view showing part of a street-car with my improved buffer applied. Fig. II is a top or plan view showing the end timber or dead-wood of a car with the buffer applied. Fig. III is a perspective view of the

20 center bracket attached to the buffer. Fig. IV is a perspective view of one of the end brackets. Fig. V is a perspective view of one of the brackets that are connected to the end timber. Fig. VI is a detail vertical section 25 taken on line VI VI, Fig. II.

I represents part of a street-car, and 2 the usual end timber or dead-wood of the car.

30 3 represents the buffer, which is made in channel-bar shape, with the channel presented inwardly.

Secured to the central part of the inner face 35 of the vertical wall of the buffer by rivets or bolts is a bracket 4, (see Fig. III,) which has U-shaped perforated loops or bends 5 to receive bolts 6, the other ends of which pass

through brackets 7, (see Figs. II and VI,) that are secured to the under side of the timber 2. Surrounding the bolts 6, between the brackets 4 and 7, are coiled springs 8.

Secured to each end of the buffer 3, on the 40 inner side of its vertical wall, is a bracket 9, (see Fig. IV,) each of these brackets having a perforated portion 10 to receive a bolt 11, the other end of which passes through a bracket 12, (see Fig. V,) secured to the under 45 side of the timber 2. Surrounding the bolts 11, between the brackets 12 and the portions 10 of the brackets 9, are coiled springs 13.

It will be observed that the buffer is located beneath the plane of the timber 2, so that its 50 movement is not interfered with by the timber, and in the event of the buffer coming against an object the springs allow it to yield to deaden the shock.

I claim as my invention—

55 In a street-car, in combination with the timber 2, a buffer consisting of a channel-bar, a bracket 4 having perforated U-shaped portions 5 secured to the central part of the buffer, brackets 9 having perforated portions 10 60 and secured to the ends of the buffer, brackets 7 and 12 secured to the under side of the timber 2, bolts connecting the brackets on the buffer to the brackets on the timber, and springs surrounding said bolts, substantially 65 as and for the purpose set forth.

PETER M. KLING.

In presence of—

E. S. KNIGHT,
M. P. SMITH.
